CUTTER HEAD

Filed Aug. 26, 1926

Inventor:
John E. Coville,
by Walter O. Lombard, Atty.

UNITED STATES PATENT OFFICE.

JOHN E. COVILLE, OF SWAMPSCOTT, MASSACHUSETTS, ASSIGNOR OF ONE-THIRD TO THEODORE W. McNICHOL, AND ONE-THIRD TO THOMAS T. McNICHOL, BOTH OF SWAMPSCOTT, MASSACHUSETTS.

CUTTER HEAD.

Application filed August 26, 1926. Serial No. 131,781.

This invention relates to cutter heads particularly adapted for use in lathes for shaping lasts and similar articles, the object being to produce a balanced cutter having 5 means for removing superfluous stock from the block prior to the actual shaping thereof, and provided with means whereby said head may be mounted directly upon the end of a rotary shaft.

10 These objects are attained by the mechanism illustrated in the accompanying drawings.

15 For the purpose of illustrating the invention, one preferred form thereof is illustrated in the drawings, this form having been found to give satisfactory and reliable results, although it is to be understood that the various instrumentalities of which the invention consists can be variously arranged 20 and organized, and the invention is not limited to the precise arrangement and organization of these instrumentalities as herein shown and described except as required by the scope of the appended claims.

25 Of the drawings:

Figure 1 represents an end elevation of a cutter embodying the principles of the present invention.

Figure 2 represents a section of same on 30 line 2, 2, on Fig. 1.

Figure 3 represents a section on line 3, 3, on Fig. 2.

Figure 4 represents a section on line 4, 4, on Fig. 2.

35 Figure 5 represents a section of line 5, 5, on Fig. 2, and

Figure 6 represents a section on line 6, 6, on Fig. 2, with the cutter blades and securing bolts therefor removed, and the nut for 40 securing the head to the shaft omitted.

Similar characters indicate like parts throughout the several figures of the drawings.

In the drawings 10 is a revoluble shaft 45 having a cone-shaped portion 11 near one end from which extends outwardly a threaded portion 12.

The block 13 of the cutter head has a conical bore which is fitted to the cone-shaped portion 11 which has its greatest diameter at its inner end.

50 The block 13 is provided with four radial slots 14 in its outer face, said slots being of

different depths and the block 13 on its opposite end is provided with a projecting cylindrical hub 15.

In each slot 14 is fitted a shaping blade 16, these blades being in different planes perpendicular to the axis of rotation of the block 13 and the outer ends of said blades 60 are curved toward the inner end of the block 13 and over the periphery thereof.

The block 13 is provided with a peripheral shoulder 16* between which and the inner end of said block is a cylindrical portion 17 65 on which are mounted side by side two balancing rings 18.

Each ring 18 is eccentric as shown in the drawings one side being much heavier than the other side.

70 The combined thickness of these rings 18 is greater than the length of said cylindrical portion 17 so that the inner ring projects beyond the end face of the cylindrical portion 17 in contact with an annular plate 19 mounted upon and movable endwise of the hub 15.

75 The eccentric rings 18 are provided with peripheral spanner holes 20 by which said rings may be accurately adjusted about the 80 axis of the block 13 to balance the weight of the heavier blades 16.

Through the block 13, annular plate 19 and blades 16, extend bolts 21 each having a head 22 bearing against the outer face of 85 a blade 16 while the opposite end has a nut 22* threaded thereto.

When the rings 18 have been adjusted properly they may be clamped to the shoulder 16* by turning the nuts 22* and forcing 90 the plate 19 toward said shoulder.

The extreme outer end of shaft 10 is threaded and has mounted thereon the nut 24, having on its inner end an annular flange 95 25 which extends into a socket in the block 13 and bears against the end wall thereof, thereby forcing said block further on the cone portion 11 of the shaft 10.

100 The nut 24 has two scoring blades 26 formed integral therewith which act upon the work ahead of the cutting blades 16, removing parts of the wooden blocks and permitting the actual shaping of the lasts to be more readily accomplished by the cutting blades 16. The outer ends of the scoring blades 26 are curved with their faces toward 105

the block 13 further from the axis of shaft 11 than their outer faces.

The nut 24 is so threaded to the shaft that when the blades 26 come into contact with the work the strain thereon will tend to screw the nut further on the shaft and at the same time crowd the block further on the cone portion 11.

The block 13 is provided with threaded holes 27 to receive screws forming a part of a tool by which said block may be withdrawn from the tapered portion 11 of the shaft 10.

This tool forms no part of the present invention and therefore is not shown or described.

By providing the cutter head with the balancing rings 18, 18 the cutter head will rotate evenly.

Moreover, the means of securing the cutter head to the rotating driving shaft is greatly simplified in applicant's construction.

By providing the scoring blades 26 much of the material of the work may be removed before the cutting and shaping blades come into operation.

The simplification in construction of the cutter head greatly reduces the cost of manufacture and by reducing to a minimum the number of movable parts there are fewer elements to get out of order and interfere with the proper operation of the lathe.

It is believed that the operation and many advantages of the invention will be understood readily without further description.

Having thus described my invention, I claim:

1. The combination with a rotary shaft; a head mounted on the end thereof and provided with radial slots in the outer face thereof at varying distances from its inner face; cutter blades disposed in said slots and secured to said head; said blades having cutting edges beyond the periphery of said head; and a nut threaded to the end of said shaft and bearing against the outer end of said head.

2. The combination with a rotary shaft; a head mounted on the end thereof and provided with four radial slots in the outer face thereof at varying distances from its inner face and perpendicular to each other; cutter blades disposed in said slots and secured to said head; said blades having curved cutting edges beyond the periphery of said head; and a nut threaded to the end of said shaft and bearing against the outer end of said head.

3. The combination with a rotary shaft; a head mounted on the end thereof and provided with radial slots in the outer face thereof; cutter blades disposed in said slots with curved cutting edges beyond the periphery of said head; a bolt securing each cut-

ter blade to said head; and a nut threaded to the end of said shaft and bearing against the outer end of said head.

4. The combination with a rotary shaft; a head mounted on the end thereof and provided with radial slots in the outer face thereof; cutter blades disposed in said slots; an annular plate surrounding a hub on the inner end of said head; a bolt extending through each cutter blade and said plate; a nut threaded to the inner end of each bolt; and a nut threaded to the end of said shaft and bearing against the outer end of said head.

5. The combination with a rotary shaft; a head mounted on the end thereof and provided with a plurality of radial slots all formed in the outer face thereof; cutter blades disposed in said slots and secured to said head; each cutter blade having at its outer end a cutting edge curved over the periphery of said head and said cutting edges being in planes overlapping each other; and a nut threaded to the end of said shaft and bearing against the outer end of said head.

6. The combination with a rotary shaft; a head mounted on the end thereof and provided with a plurality of radial slots all formed in the outer face thereof; cutter blades disposed in said slots and secured to said head; said cutter blades having at their outer ends cutting edges curved over the periphery of said head and terminating at different distances from the inner end of said head, said cutting edges being in planes overlapping each other; and a nut threaded to the end of said shaft and bearing against the outer end of said head.

7. The combination with a rotary shaft having at one end an axially disposed threaded extension; a head mounted near one end of the shaft provided with a plurality of shaping blades; a nut on said threaded extension and locking said head to said shaft; and a plurality of scoring blades integral with said nut with the outer faces of their outer ends curved towards said head.

8. The combination with a rotary shaft having a cone-shaped portion near its outer end; a head with a conical bore fitted to said cone-shaped portion and provided with a plurality of radial slots all formed in the outer face thereof; cutter blades disposed in said slots and secured to said head; said blades having at their outer ends curved cutting edges extending toward the opposite face of said head; and a nut threaded to the end of said shaft and bearing against the outer end of said head, said nut being adapted to force said head endwise on said cone-shaped portion and lock it thereto.

9. The combination with a rotary shaft having a cone-shaped portion near its outer end and a threaded portion extending out-

wardly therefrom; a head with a conical bore fitted to said cone-shaped portion; cutter blades secured to said head and projecting radially therefrom, said blades having curved cutting edges beyond the periphery of said head and in overlapping planes; and a nut on said threaded portion adapted to force said head towards the larger end of said cone-shaped portion and lock it thereto.

10 10. The combination with a rotary shaft; a head mounted thereon and revoluble therewith having a shoulder near its outer end and a cylindrical portion between said shoulder and its inner end; cutter blades radiating from said head; an annular plate

surrounding a hub on the inner end of said head and revoluble therewith; two eccentric balancing rings on said cylindrical portion and independently adjustable about the axis thereof, the combined widths of said eccentric rings being greater than the length of said cylindrical portion; and means carried by said head for moving said annular plate towards said shoulder and clamping said eccentric rings to prevent movement thereof about the axis of said head.

Signed by me at Lynn this 16th day of August 1926.

JOHN E. COVILLE.
